COMBINATION FISHING ROD AND REEL

Arthur C. Shafer, Cincinnati, Ohio

Application May 26, 1949, Serial No. 2,895

Term of patent 14 years

(Cl. D31—4)

To all whom it may concern:

Be it known that I, Arthur C. Shafer, a citizen of the United States, residing at Cincinnati, in the State of Ohio, have invented a new, original, and ornamental Design for a Combination Fishing Rod and Reel, of which the following is a specification, reference being had to the accompanying drawings, forming a part thereof.

Figure 1 is a side elevation of a combination fishing rod and reel showing my new design.

Figure 2 is a plan view.

Figure 3 is a bottom plan view.

Figure 4 is a cross section thereof taken on the section line 4—4 of Figure 1.

Figure 5 is a fragmentary rear elevation showing the reel support and reel.

I claim:

The ornamental design for a combination fishing rod and reel, as shown.

ARTHUR C. SHAFER.
